(57) CLAIM

The ornamental design for hand stamp case, as shown and described.

DESCRIPTION

FIG. 1 is a perspective view of the subject hand stamp case; FIG. 2 is a front plan view thereof;

FIG. 3 is a right side view thereof (the left side view being a mirror image of the right side view);

FIG. 4 is a rear view thereof; and,

FIG. 5 is a top plan view thereof.

The broken line showing of the base of the design in FIGS. 1, 2, 3 and 4 is for illustrative purposes only and forms no part of the claimed design.
